Heller Engineering & Management Co., Los Angeles,
Calif., a corporation of California

Filed July 12, 1968, Ser. No. 12,717

Term of patent 14 years

Int. Cl. D12—14

U.S. Cl. D14—3

FIG. 1 is a perspective view of a fork lift attachment incorporating my new design, the fork lift truck shown in phantom lines being illustrated for the purpose of showing environmental use.

FIG. 2 is a perspective view similar to FIG. 1 and showing the fork lift attachment in an alternate position.

FIG. 3 is an elevational view of the side of the fork lift attachment opposite the side shown in FIG. 2.

FIG. 4 is a rear elevational view of the fork lift attachment.

I claim:

The ornamental design for a fork lift attachment, substantially as shown.
